DEERE & COMPANY, OF MOLINE, ILLINOIS, A CORPORATION OF ILLINOIS

CORN HARVESTER

Application filed November 8, 1929. Serial No. 405,591.

This invention relates to corn harvesters having a discharging elevator which conveys the corn ears from the harvester to a wagon which is drawn along at one side of 5 the harvester by a tractor which pulls the harvester, and has to do primarily with the construction of the elevator and the hopper connected therewith, which hopper receives the corn ears from the husking rolls and de- 10 liveres them to the elevator.

Corn harvesters are quite wide when in operative position in the field, and it is therefore desirable that when transporting them their over-all width be reduced to a minimum 15 so as to facilitate passage of the machine through farm lanes, gates, doorways, etc. It is also desirable in a machine of this type that it be well balanced when being transported, and in order to so balance the ma- 20 chine it is necessary that the center of gravity of the elevator be brought between the two carrying wheels when the elevator is swung upward to place it in transport position so that the weight of the elevator will be carried by both wheels. In prior constructions 25 the outer or discharge end of the elevator can be swung upwardly to some extent to reduce the over-all width of the machine, but it still projects to an objectionable degree 30 beyond the side or tread width of the machine, preventing passage through narrow spaces, nor can such prior constructions of elevators be swung upwardly far enough so that the center of gravity of the elevator is 35 brought between the two carrying wheels, and this is so because of the fact that the hop- 40 per at the lower end of the elevator which receives the corn ears from the husking rolls is permanently secured in fixed position to the lower end portion of the elevator, said hopper preventing upward movement of the elevator 45 beyond the plane of the outer end of the hopper. With this old construction the hopper was so designed that the elevator could be swung upwardly to some extent for transport, but when so swung up it still projected considerably from the side of the machine, and the center of gravity of the elevator was in a plane outside of the plane 50 of the carrying wheel on the elevator side of

the harvester. Also, in such old constructions, by designing the hopper so as to permit this limited upward swinging movement of the elevator said hopper did not effectively receive the ears from the husking rolls. 35

With the above in view, it is the principal object of our invention to provide a hopper so connected with the elevator near its lower end portion as to be movable with relation to the elevator for accommodating movement of the elevator into a substantially vertical position when the harvester is to be transported. 60

Another object of our invention is to provide such a construction of elevator and hopper whereby the elevator may be swung to such a position as to bring the center of gravity of the elevator inside the carrying wheels when the harvester is to be transported. 55

A further object is to provide a combined elevator and hopper of such construction that the hopper may be easily and quickly moved out of operative position as desired to permit movement of the elevator into a substantially vertical position when the harvester is to be transported. 75

Further objects and advantageous features will appear from the following description of our invention taken in connection with the accompanying drawing, in which— 80

Figure 1 is a rear view of a corn harvester showing the discharge elevator and its movable hopper in operating position, and illustrating the hopper in full lines in its operative position and in dotted lines in its in-operative or transport position; 85

Figure 2 is a perspective view of a portion of the rear side of the machine looking from a forward point on the right hand side thereof as shown in Figure 1, showing the elevator and its hopper in transport position; and 90

Figure 3 is an enlarged cross-sectional view taken on the line 3—3 of Figure 1.

The general design of the corn harvester illustrated in the drawing is of conventional form and will be but briefly described. As shown, 5 indicates the harvester as a whole supported on carrying wheels 6, the rear two of which are shown in Figure 1. The harvester illustrated comprises the usual gather- 95

ers 7 between which are mounted the snapping rolls 8. Suitable elevator or conveying mechanism (not shown) is provided for conveying the corn ears from the snapping rolls 8 to the husking rolls 9, see Figure 3, which remove the husks from the ears, said husking rolls being enclosed by the usual husking box 9a carried by the frame. The harvester illustrated is adapted to be drawn by a tractor, 10 and the power for operating the snapping rolls, elevators, husking rolls, etc., is preferably derived from the engine of the tractor through a suitable power take-off device, although it may be derived from a separate 15 motor on the harvester or from the traction power of the wheels 6.

An elevator, indicated as a whole by the reference numeral 11, is supported at its lower end on the harvester adjacent to the 20 right hand rear corner thereof as shown in Figure 1, and it is connected to the harvester by a pair of brackets 12 secured at one end by rivets or bolts to the lower portions of the opposite side walls of the elevator, the opposite 25 ends of said brackets embracing a drive shaft 13 suitably journaled at opposite sides of the elevator in bearings carried by frame members of the harvester, as shown in Figure 3. This drive shaft 13 is provided 30 for driving the elevating mechanism within the elevator 11, and it is driven by a driving chain 14 running over a sprocket wheel 15 keyed or otherwise secured thereto. The bottom 16 and sides 17 of the elevator are formed 35 of a single piece of sheet metal bent as shown in Figure 3. Suitably supported between the side walls of the elevator is a board 18 which extends from the lower to the upper end of the elevator and along which the corn ears 40 are conveyed to the upper end thereof for delivery to a wagon which is drawn along at one side of the harvester by the tractor. The elevator is provided at its upper and lower ends with sprocket wheels 19, the lower 45 one of which is shown in Figure 3. This lower sprocket wheel is keyed to the elevator drive shaft 13 so as to be driven thereby. A driving chain 21 is trained over said sprocket 50 wheels 19, and at spaced intervals therealong it is provided with conveying paddles 22 which in operation are moved along the upper surface of the board 8 in their upward movement, said paddles conveying the corn 55 ears up through the elevator for discharge through the outlet chute 23 into the wagon. The parts of the harvester and elevator thus far described having nothing to do, in and of themselves, with the present invention, and 60 it is believed that the brief description thereof given will suffice.

Coming now to the parts of the harvester to which our present invention relates, 24 indicates our improved movable hopper which 65 is connected to the elevator on the upper side

portion thereof near its lower end. In Figure 1 the hopper is shown in operative position, while in Figure 2 it is shown in inoperative position. When in operative position it occupies the space between the outer 70 ends of the husking rolls and the lower end of the elevator for receiving the corn ears discharged from said rolls, after the husks have been removed, for delivering the same to the elevator. The hopper comprises outwardly flared side wall members 25, 26 and a rear wall member 27. The lower edge of each of the side wall members 25, 26 is bent 75 downwardly, as shown in Figure 3, to provide lip portions 28. Spaced a short distance from each of these lip portions is a metal strip 29, see Figure 3, the upper edge of which is suitably secured to the respective side member 25, 26, while the lower edge portions of each of said strips 29 extends 80 parallel with its respective lip portion 28. The parts 28 and 29 on either side of the hopper, as will be seen from said figure, form a slot or groove for accommodating the adjacent top edge of the two opposite sides of the elevator, so as to completely close the space 85 between the sides of the elevator and the hopper, as will be readily understood.

The back wall member 27 of the hopper is provided at its lower edge with a toothed 90 member 31 suitably hinged thereto at 32, and so arranged that it can swing upwardly. Downward movement of the member 31 is prevented in any well known manner, so that the ears cannot fall back past the same toward the husking rolls.

The hopper 24 is held down on the elevator 11 by its own weight and the frictional engagement between the members 28, 29 at either side of the hopper and the respective side walls 17 of the elevator, but in order to prevent accidental movement upwardly of said hopper when the harvester is in operation and the corn ears are being delivered to the hopper from the husking rolls, we provide a pair of links 33, one on each side of the hopper, which links are pivotally connected at one end to the side walls of the hopper as shown at 33a, while the opposite ends of said links are pivotally connected at 33b to the respective side walls of the elevator, as shown in Figure 1. Suitably secured on each side wall 17 of the elevator adjacent to the link 33 is a spring clip 34, so positioned that when the hopper is in its operative position down on the elevator, as shown in Figure 1, the spring clips partially embrace the links 33, thereby preventing movement of said links and holding the hopper down firmly in position.

The elevator is held in its working or operative position as shown in Figure 1, in which position it delivers the corn ears to the adjacent wagon, by means of a rod 35 pivoted at one end to a bracket 35' fixed to the 130

harvester frame. The opposite end of the rod 35 is pivotally connected to a V-shaped rod member 36, the opposite ends of which are pivotally connected at 37 to the opposite 5 side walls of the elevator 11, as shown in Figure 2.

When the harvester is to be transported, it is desirable that the elevator be swung to a vertical position, as before mentioned, and 10 this is accomplished by swinging the hopper relatively to the elevator, without disconnecting it from the elevator, by means of the links 33 which are pivotally connected to the hopper and to the elevator. The hopper is first 15 forcibly pulled out of the position shown in Figure 1, to move the parts 28, 29 of the hopper away from the side walls 17 of the elevator, the spring clips 34 being resilient enough so that they will spring back sufficiently to 20 disengage from the links 33. The hopper is then swung into the position shown in dotted lines in Figure 1, the links 33 turning on their pivot connections 33b with the side walls 17 of the elevator, while the hopper swings on its pivot connections 33a with the links 33. As shown in Figure 2, when the hopper 24 is swung out of operative position the opposite side walls 25, 26 thereof are positioned at opposite side of the elevator, such side 30 walls being thus permitted to embrace the elevator because there is no bottom portion extending between said side walls. It will thus be seen that with the hopper swung up to the position shown in 35 dotted lines in Figure 1 and full lines in Figure 2 it will not interfere with the movement of the elevator into a vertical position, such as that shown in Figure 2. In such vertical position the outer side of the elevator 40 lies substantially in the plane of the adjacent supporting wheel 6, or inwardly of said plane, so that the elevator does not project beyond the tread width of the wheels 6. Such position also places the center of gravity 45 of the elevator between the two wheels so that the weight of the elevator is borne on both wheels.

Two swinging hooks 38 are provided, one pivotally mounted on each side of the elevator, which are adapted to hook around an ear retarding control shaft of the machine, indicated by the numeral 39, to hold the elevator in its vertical position during transport. Such shaft 39 constitutes a control 55 member disposed substantially at the ends of the husking rolls and transversely thereto, and serving through the manipulation of a control handle or handles 41 to raise or lower a cover 42 from which depend the retard 60 tating plates which retard or hold the ears of corn against the husking rolls, all as disclosed in the copending application of Louis A. Paradise and Wilbur J. Coulter on Corn picking machines, Serial No. 242,370, filed 65 December 24, 1927.

By reason of the pivotal connection between the rod 35 and the V-shaped rod member 36 these two members will have jack-knife movement relative to each other when the elevator is moved into and out of operative position. 70

We claim:

1. The combination with a corn harvester having husking rolls and a discharge elevator adapted to receive corn ears from said husking rolls, of means movably mounted on said elevator adapted to receive said corn ears from said husking rolls and deliver them to said elevator. 75

2. The combination with a corn harvester having husking rolls and a discharge elevator adapted to receive corn ears from said husking rolls, of means movably mounted on said elevator adapted to receive said corn ears from said husking rolls and deliver them to said elevator, said means being positioned between said elevator and said husking rolls. 80

3. The combination with a corn harvester having husking rolls and a discharge elevator adapted to be moved into and out of operative position and to receive corn ears from said husking rolls when in operative position, of means movably mounted on said elevator adapted to receive said corn ears from said husking rolls and deliver them to said elevator, said means being positioned between said elevator and said husking rolls when in operative position, and adapted to be moved out of such position when the elevator is in inoperative or transport position. 95

4. The combination with a corn harvester having an elevator for discharging corn ears therefrom, means mounting said elevator on said harvester for movement into and out of operative position, of a hopper mounted on said elevator for guiding the corn ears to said elevator, and means connecting said hopper with said elevator whereby said hopper may be moved into and out of operative position relative to said elevator. 105

5. The combination with a corn harvester having an elevator for discharging corn ears therefrom and movable into and out of operative position, of a hopper mounted on said elevator in proximity to said harvester for guiding the corn ears to said elevator, and means connecting said hopper with said elevator whereby said hopper may be moved into and out of operative position relative to said elevator. 115

6. The combination with a corn harvester having an elevator for discharging corn ears therefrom, means mounting said elevator on said harvester for movement into and out of operative position, of a hopper for guiding the corn ears to said elevator pivotally mounted on said elevator and adapted to be moved into and out of operative position. 125

7. The combination with a corn harvester having an elevator for discharging corn ears therefrom, means mounting said elevator on said harvester for movement into and out of operative position, of a hopper for guiding the corn ears to said elevator pivotally mounted on said elevator in proximity to said harvester and adapted to be moved into and out of operative position.
- 10 8. The combination with a corn harvester having an elevator for discharging corn ears therefrom, means supporting the elevator for movement into and out of operative position, of a hopper for guiding the corn ears to said elevator, and means connecting the elevator with said hopper for moving said hopper on said elevator into and out of operative position.
- 15 9. The combination with a corn harvester having an elevator for discharging corn ears therefrom, means supporting the elevator for movement into and out of operative position, of a hopper for the receiving end of said elevator, and means for pivotally connecting said hopper to said elevator, said means comprising links pivotally connected with said hopper whereby said hopper is adapted to be moved into and out of operative position.
- 20 10. The combination with a corn harvester having an elevator for discharging corn ears therefrom, means supporting the elevator for movement into and out of operative position, of a hopper for the receiving end of said elevator, and means for pivotally connecting said hopper to said elevator, said means comprising links pivotally connected with said hopper and with said elevator whereby said hopper is adapted to be moved into and out of operative position.
- 25 11. The combination with a corn harvester having an elevator for discharging corn ears therefrom, means supporting the elevator for movement into and out of operative position, of a hopper for the receiving end of said elevator, and means for pivotally connecting said hopper to said elevator, said means comprising links pivotally connected with said hopper and with said elevator for moving said hopper into and out of operative position, and means mounted on said elevator and coacting with said links for preventing accidental movement of said links when the hopper is in operative position.
- 30 12. The combination with a corn harvester having an elevator for discharging corn ears therefrom, means supporting the elevator for movement into and out of operative position, of a hopper for the receiving end of said elevator, and means for pivotally connecting said hopper to said elevator, said means comprising links pivotally connected with said hopper and with said elevator for moving said hopper into and out of operative position, and detent clips mounted on said elevator and coacting with said links for preventing acci-
- dental movement of said links when the hopper is in operative position.
- 35 13. The combination with a corn harvester having an elevator for discharging corn ears therefrom, and means supporting the elevator for movement into and out of operative position, of a hopper for the receiving end of said elevator, means connecting said hopper with said elevator whereby said hopper may be moved into and out of operative position relatively to said elevator, and means on the lower edges of the sides of said hopper for receiving the upper edges of the side walls of the elevator to close the opening between said hopper and said elevator when said hopper is in operative position.
- 40 14. The combination with a corn harvester having husking rolls and a discharge elevator, means supporting the elevator for movement into and out of operative position, said elevator adapted to receive corn ears from said husking rolls when in operative position, of a hopper, means connecting said hopper with said elevator whereby said hopper may be moved into and out of operative position relative to said elevator and to receive the corn ears from said husking rolls and guide them to said elevator when in operative position, said hopper being adapted to be moved out of operative position when the elevator is moved out of operative position.
- 45 15. The combination with a corn harvester having an elevator for discharging corn ears therefrom, of a hopper for guiding the corn ears to said elevator, means connecting said hopper with said elevator whereby said hopper may be moved into and out of operative position relative to said elevator, the side walls of said hopper embracing said elevator when in inoperative position.
- 50 16. The combination with a corn harvester having an elevator for discharging corn ears therefrom, means mounting said elevator on said harvester for movement into and out of operative position, of a hopper for guiding the corn ears to said elevator, means connecting said hopper with said elevator whereby said hopper may be moved into and out of operative position relative to said elevator, the side walls of said hopper extending substantially parallel to said elevator when moved into operative position and transversely to said elevator when moved to inoperative position.
- 55 17. The combination with a corn harvester having a frame and an elevator pivotally mounted on said frame in a position to receive ears of corn therefrom, of a hopper means including parallel strips detachably engaging said elevator for mounting said hopper in the space between the harvester and elevator for guiding corn ears into the latter, said means permitting said hopper to be removed from its normal position to

permit the elevator to be moved out of its receiving position.

18. The combination with a corn harvester having an elevator for discharging corn ears therefrom and means mounting said elevator on said harvester for movement into and out of operative position, of a hopper normally positioned between said elevator and said harvester when the elevator is in operative position for guiding the corn ears to said elevator, and means detachably engaging said elevator for supporting said hopper in said operative position said means providing for shifting said hopper out of operative position 15 when said elevator is moved to its inoperative position.

19. The combination with a corn harvester having a frame, a husking box mounted on said frame, an elevator pivotally mounted at 20 its lower end on said frame adjacent the end of said husking box and normally held in an upwardly inclined position, of a hopper disposed in the space between the end of the husking box and the lower end of the elevator 25 for guiding corn ears from the husking box into the elevator, means for securing said hopper in said position, said means being arranged to facilitate removal of the hopper therefrom to permit the elevator to be raised 30 in a position of substantial parallelism with the end of the husking box.

20. The combination with a corn harvester having an elevator for discharging corn ears therefrom and means mounting said elevator 35 on said harvester for movement into and out of operative position, of a hopper, and means on the hopper slidably engaging the elevator

for supporting said hopper between said elevator and said harvester for guiding the corn ears to said elevator when said elevator is in operative position, said means being operable out of engagement with the elevator 70 to move said hopper out of said normal position when the elevator is moved to inoperative position.

21. The combination with a corn harvester having an elevator for discharging corn ears therefrom and means mounting said elevator on said harvester for movement into and out of operative position, of a hopper, and means for pivotally supporting said hopper between 75 said elevator and said harvester for guiding the corn ears to said elevator when said elevator is in operative position, said means being operable to swing said hopper out of said normal position when the elevator is moved to inoperative position.

22. The combination with a corn harvester having an elevator for discharging corn ears therefrom and means mounting said elevator on said harvester for movement into and out of operative position, of a hopper, and means including pivoted links supporting said hopper whereby said hopper may be moved into operative position between said elevator and said harvester for guiding corn ears to said elevator when said elevator is in operative position, and moved out of operative position when the elevator is moved to its inoperative position.

In witness whereof, we hereunto subscribe our names this 4th day of November, 1929.

WILBUR J. COULTAS.
NOLAN D. COLVIN.
